ROTARY PUMP

Ernest A. Cuny, New York, N. Y.

Application August 14, 1951, Serial No. 241,795

4 Claims. (Cl. 103—120)

1

The invention herein disclosed relates to rotary pumps of the type disclosed in Patent No. 2,242,058 of May 13, 1941, in which displacement is effected by cooperatively related, bladed and slotted rotors operating on intersecting axes within an enclosed housing.

Objects of the present invention are to improve the operating efficiency of such devices, to simplify construction and to reduce production costs.

Particularly it is a purpose of the invention to join the cooperating rotor elements in a self-centering ball and socket form of universal joint.

A further special object of the invention is to provide a rotary pump of the character indicated which will be self-adjusting in respect to pressure and thereby adapted to deliver fluid under substantially constant pressure.

Other desirable objects attained by the invention are set forth or will appear in the course of the following specification.

The drawings accompanying and forming part of the specification illustrate certain present commercial embodiments of the invention. Structure, however, may be modified and changed as regards the immediate disclosure, all within the true intent and broad scope of the invention as hereinafter defined and claimed.

Fig. 1 in the drawings is a broken cross sectional view of one of the pumps; Fig. 1a is a broken sectional detail of the universal joint.

Figs. 2 and 3 are broken face views of the companion inlet and outlet sections of the pump casing;

Fig. 4 is a sectional view of the upper portion of the pump casing on substantially the plane of line 4—4 of Fig. 1, showing the cross connection of the inlet and outlet passages;

Fig. 5 is an enlarged broken sectional detail of the mid-portion of the pump casing, on substantially the plane of line 5—5 of Fig. 2;

Fig. 6 is a face view of the slotted disc rotor;

Fig. 7 is a broken detail view showing how the rounded edges of the slotted rotor fit in rolling engagement with the blades of the other rotor;

Fig. 8 is a sectional view of a modified form of the invention in which volume is automatically controlled according to pressure;

Fig. 9 is a broken and part sectional end view of this form of the pump;

Fig. 10 is a sectional view as on substantially the plane of line 10—10 of Fig. 8;

Fig. 11 is a broken part sectional view of the segmental form of bladed rotor shaped for universal joint engagement over the ball center of the slotted rotor.

Figs 1 and 8 illustrate the arrangement of the

two shafts 15 and 16 on intersecting axes, with the first shaft carrying a bladed rotor 17 turning concentrically in the generally cylindrical pump chamber 18, and the second shaft carrying a disc rotor 19 slotted at 20 to accommodate the blades 21 of the first rotor.

The inclination of the disc 19, rotating in the same pump chamber together with the blades, produces displacement of opposite effect at opposite sides of the disc and at diametrically opposite points of the pump casing.

The pump casing is shown made up of two sections 22, 23, secured together in flat, face-to-face engagement by screws 24.

15 The section 22 has an inlet 25 opening into an arcuate channel 26 partly surrounding the pump chamber 18 and opening into this inlet portion of the pump chamber by an arcuate slot 27.

At a point almost diametrically opposite the intake 25 the arcuate channel 26 terminates in a cross-over port 28 registering with a corresponding port 29 in the face of the other housing section 23, the latter port being open to the arcuate inlet channel 30 which opens through segmental port 32 into the diagonally opposite intake portion of the pump chamber, as will be clear from Fig. 4.

At a diametrically opposite portion of the pump chamber an arcuate slot 33 places the pump chamber in communication with a surrounding arcuate discharge channel 34 in section 23, terminating in a port 35 in register with port 36 of casing section 22, which latter port communicates with arcuate channel 37 in communication with the diagonally opposite discharge portion of the pump chamber through an arcuate slot 38, Fig. 4.

The slots 27 and 32, as shown in Fig. 4, are displaced laterally or transversely of the pump axis to locate them to the intake portions at opposite sides of the slotted disc rotor 19 and similarly, the slots 33 and 38 are offset to the discharge portions of the pump chamber at diagonally opposite sides of the disc rotor.

Consequently the volumetric displacement at opposite sides of the angularly or inclinedly related rotors is fully utilized and pressure is substantially balanced at opposite sides of the rotors.

The arcuate or segmental inlet and outlet slots substantially balance transverse pressure on the rotors, leaving them free to operate with low frictional losses.

The two rotor shafts are shown connected by double ball and socket joints.

In Fig. 1 the shaft 15 carries an inner ball element 39 having a socket receiving the transverse roll member 40 on the end of the shaft 16, form-

ing a universal joint drive connection. The shaft 16 is tapered to fit a correspondingly tapered socket in the outer ball and socket element 41 of the shaft 16, being secured in this relation by nut 53.

Shaft 15 also carries an outer ball and socket element 42 journaled in the housing section 22 and receiving the ball portion of the outer ball and socket element 41 of shaft 16.

The outer ball and socket element 42 of shaft 15 which, in effect, constitutes the bladed rotor 17, may be made up as shown in Fig. 11, with the socket forming portions of the blades 21 in separate segments 43 which can be secured over the ball portion 41 of the other shaft by screws 44.

In the construction shown in Fig. 8 the inner ball and socket connection indicated at 40 in Fig. 1, is omitted, the ball member 39 of shaft 15 engaging within the ball and socket member 41 of shaft 16 and the latter fitting within the ball and socket element 42 of shaft 15.

The shafts may have a fixed angular relation as shown in Fig. 1, where said shafts are journaled in fixed, angularly related bearings 45, 46, or the angular relationship may be adjustable as for variable displacement or pressure control purposes.

Figs. 8 and 9 show the second shaft, 16, journaled at 47 in rectangular bearing box 48 slidably guided in a parallel-sided bearing housing 49.

A spring 50 is adjustably mounted at 51 in this bearing housing, tensioned against the sliding bearing block 47 to hold it in the position of maximum shaft angularity and hence in the position of maximum pump displacement.

With increase of pressure developed in the pump chamber against the slotted disc rotor, the spring will be compressed, yielding, under sufficient pressure, possibly to the position of zero displacement, with shaft 16 in line with shaft 15.

By proper selection and setting of spring 50, the pump may be made self-controlling for pressure or displacement.

This self-controlling feature renders the pump particularly desirable for such uses as rocket fuel pumps.

While described as a pump, it will be realized that the rotary displacement machine disclosed may have many other uses and the present disclosure will be so understood.

Fig. 7 shows in detail how the slots 20 may be cut in the disc forming rotor 19 on curved lines 52 so as to make easy rolling engagement with the sides of the blades 21.

The universal joint connection 39, 40, Figs. 1 and 1a, may be set so as to maintain a running clearance between the edges of the blades and the edges of the slots. To facilitate such setting the shaft 16 carrying the cross roll 40 of the universal joint may be tapered and be secured by the nut 53, Fig. 1, in a taper seat in the bearing sleeve portion 54 which carries shaft 16.

The various parts of the pump may be cast, molded or otherwise formed in ferrous or non-ferrous metals or in hard plastic or hard rubber, enabling the pump to be made for handling different kinds of fluids.

Additional advantages are that the machine is reversible and is suited to operation at varying rates ranging from low to high speed operation.

What is claimed is:

1. The rotary machine herein disclosed com-

prising companion bladed and slotted disc rotors rotating on intersecting axes with the blades of the first rotor in the slots of their disc rotor, shafts carrying said rotors, a ball and socket member at the end of one of said shafts and a ball and socket member at the end of the other of said shafts, the ball and socket member of one shaft receiving the ball and socket member of the other shaft and said first shaft having a ball member fitting within the socket portion of the ball and socket member of said other shaft.

2. The rotary machine herein disclosed comprising companion bladed and slotted disc rotors rotating on intersecting axes with the blades of the first rotor in the slots of the disc rotor, shafts carrying said rotors, a ball and socket member at the end of one of said shafts and a ball and socket member at the end of the other of said shafts, the ball and socket member of one shaft receiving the ball and socket member of the other shaft and said first shaft having a ball member fitting within the socket portion of the ball and socket member of said other shaft, and said ball and socket member of the first shaft constituting the bladed rotor and the socket portion of said ball and socket member being made in ball socket blade forming segments.

3. The rotary machine herein disclosed comprising companion bladed and slotted disc rotors rotating on intersecting axes with the blades of the first rotor in the slots of the disc rotor, shafts carrying said rotors, a ball and socket member at the end of one of said shafts and a ball and socket member at the end of the other of said shafts, the ball and socket member of one shaft receiving the ball and socket member of the other shaft and said first shaft having a ball member fitting within the socket portion of the ball and socket member of said other shaft, and a universal joint drive connection between said ball member and the end of said other shaft.

4. The rotary machine herein disclosed comprising companion bladed and slotted disc rotors rotating on intersecting axes with the blades of the first rotor in the slots of the disc rotor, shafts carrying said rotors, a ball and socket member at the end of one of said shafts and a ball and socket member at the end of the other of said shafts, the ball and socket member of one shaft receiving the ball and socket member of the other shaft and said first shaft having a ball member fitting within the socket portion of the ball and socket member of said other shaft, a bearing for one of said shafts adjustable transversely of the shaft axis and means for variably positioning said adjustable bearing.
